UNITED STATES PATENT OFFICE.

CARL A. STROM, OF FLORAL PARK, NEW YORK.

AEROPLANE-RUDDER.

1,313,839.

Specification of Letters Patent. Patented Aug. 19, 1919.

Application filed June 28, 1918. Serial No. 242,478.

To all whom it may concern:

Be it known that I, CARL A. STROM, a citizen of the United States, and a resident of Floral Park, in the county of Nassau and 5 State of New York, have invented a new and Improved Aeroplane-Rudder, of which the following is a full, clear, and exact description.

My invention relates to aeroplane rudders 10 or flaps, and it has reference more particularly to a rudder or flap adapted to direct air current therethrough, with means for varying the position of the rudder or flap to change the direction of the air current, 15 whereby the direction of the machine may be controlled.

An object of the invention is to provide 20 a simple and efficient rubber or flap which is mounted to revolve on an axis or axes at right angles.

Another object of the invention is to provide 25 a single rudder which will take the place of vertical and horizontal rudders hitherto employed for the guiding of flying machines.

With the above and other objects in 30 view, the nature of which will more fully appear as the description proceeds, the invention consists in the novel construction, combination and arrangement of parts as herein fully described, illustrated and claimed.

In the accompanying drawings, forming 35 part of the application, similar characters of reference indicate corresponding parts in all the views.

Figure 1 is a side elevation of the rear 40 end of an aeroplane provided with a rudder embodying my invention, a portion of the structure being broken out to show the details of construction;

Fig. 2 is a top plan view of the rudder structure; and

Fig. 3 is a front elevation of the rudder 45 and its mounts.

The rudder 5 is in the shape of a truncated hollow cone open at both ends. It is preferably flattened so that the ends of the truncated cone are elliptical. The rudder 50 is mounted to oscillate on the longer axis of the larger end. For this purpose a shaft 6 is provided within a frame 7. The frame, in turn, is mounted to rotate in a frame 8, which frame is secured to the fuselage 9 of the aeroplane to present the larger

end of the rudder 5 in proximity of the fuselage and at a suitable position to receive the air current created by the movement of the flying machine. The axis of rotation of the frame 7 is at right angles to the 60 axis of oscillation of the rudder 5. The rotation of the frame 7 is controlled by flexible members 10 connected to a tilter 11 which is rigidly secured to one of the trunnions of the frame 7. The oscillation of 65 the rudder 5 is controlled by flexible members 12 which pass to diametrically-opposite pulleys 13 positioned on the axes of rotation of the frame 7.

From the above description it will be 70 seen that the rudder 5 can be turned about two axes at right angles to one another, in consequence giving any desired direction to the air current passing through the rudder. In view of the fact that the cross-sectional area of the rudder decreases toward 75 the exhaust end of the rudder, the pressure to the outflow increases, and, therefore, the pressure upon the rudder; and in accordance with the position of the rudder, that pressure 80 will produce its effect upon the flying machine with which the rudder is provided. It is self-evident that the outer surfaces of the rudder will act in a manner similar to a plain rudder utilized for that purpose, 85 the added effect being that of the pressure caused by the current flowing through the rudder in the desired direction to increase 90 the effect of the rudder upon the flying machine.

While I prefer to mount the rudder so that the axes of rotation of same are in proximity of the larger end, it is not at all necessary. The axes of rotation may be midway between the ends or nearer to either 95 end. The rudder may be positioned to be in the longitudinal axis of the fuselage, above or below the same, according to the construction of the fuselage and the effect desired from the current flowing through the 100 rudder.

When the contrivance is used as a flap on the main wings or at the end of the stabilized planes, it will only be mounted to rotate on an axis disposed parallel to the plane 105 for which it forms a flap. It must be understood that under the term "aeroplane" any flying machine is understood.

While I have described the principle of operation, together with the device which I 110

now consider to be the best embodiment thereof, I desire to have it understood that the device shown is merely illustrative and that such changes may be made as are within the scope of the appended claims.

I claim:

1. A rudder for aeroplanes in the shape of a hollow flattened frustocone open at the ends and mounted to rotate on axes at right angles, and means for turning said rudder on its axes.
- 10 2. A rudder for aeroplanes in the shape of a hollow flattened frustocone open at the ends and mounted to rotate on axes at right angles, and also to present the larger end to the air current, and means for turning said rudder on its axes.
- 15 3. A rudder for aeroplanes in the shape of a hollow frustocone open at the ends, the ends of said cone having the shape of an elongated ellipse, said rudder being mounted to rotate on the axes of the ellipse, and means for turning said rudder on said axes.

4. A rudder for aeroplanes in the shape of a hollow flattened frustocone, the ends of which are in the shape of an elongated ellipse, the ends of said cone being open, said cone being mounted to oscillate on the axes of the ellipse and adapted to present the larger end to the air current, and means for turning said rudder on said axes.

5. A rudder for aeroplanes in the shape of a truncated cone having in cross section the shape of an elongated ellipse, supporting means for said rudder in which the rudder is mounted to oscillate the axes of the elongated ellipse, said rudder being open at the ends, the larger end being adapted to receive the air current, and means for oscillating the rudder on its axes.

35 6. A control device for aeroplanes in the shape of a hollow flattened frustocone open at the ends and adapted to be mounted to present the larger end to the air current.

40

CARL A. STROM.
